UNITED STATES PATENT OFFICE.

ARTHUR W. WADSWORTH, OF FORT THOMAS, KENTUCKY, ASSIGNOR TO THE WADSWORTH WATCH CASE COMPANY, OF DAYTON, KENTUCKY, A CORPORATION OF KENTUCKY.

CASE.

1,321,867.

Specification of Letters Patent. Patented Nov. 18, 1919.

Application filed January 6, 1919. Serial No. 269,828.

To all whom it may concern:

Be it known that I, ARTHUR W. WADSWORTH, a citizen of the United States, and a resident of Fort Thomas, in the county of Campbell and State of Kentucky, have invented certain new and useful Improvements in Cases, of which the following is a specification.

My invention relates to cases, such as 10 watch cases and the like, and its object is to simplify the construction and increase the strength and durability of watch cases or the like having one or more appendages. A further object is to increase the accuracy with 15 which the different parts of the case fit together when the case is completed and thereby render the case more proof against the entrance of foreign substances, such as dirt or moisture. It is also the object of my invention to lessen the cost of construction of 20 watch cases.

My invention consists in the new and improved article of manufacture herein described and claimed, as well as in the combination of parts and in the details of construction and arrangement of parts associated together with this new and improved article of manufacture as will hereinafter be more fully described and claimed.

30 In the drawing:

Figure 1 is a front view of a watch case embodying my invention;

Fig. 2 is a vertical cross-section on a plane corresponding to the line 2-2 of Fig. 1;

35 Fig. 3 is a vertical longitudinal section on a plane corresponding to the line 3-3 of Fig. 1;

Fig. 4 is a detail side elevation of the watch-case center;

40 Fig. 5 is a bottom plan view of the same;

Fig. 6 is a front view of the movement ring;

Fig. 7 is a bottom plan view of the same;

45 Fig. 8 is a longitudinal section, corresponding to Fig. 3, of a modified watch-case center;

Fig. 9 is a similar view showing another modification; and

50 Fig. 10 is a partial similar view, enlarged, illustrating the process of making the center shown in Fig. 9, with the center in the preliminary stages shown by solid lines and

their parts thereafter formed being shown by dotted lines.

The watch case taken for example herein 55 is that of a wrist-watch having strap lugs at opposite sides through which pass the straps for holding the watch on a person's wrist. The other appendage which this watch case has is the stem-lug. It will be understood, 60 however, that my invention is not limited to cases of the particular design shown, but is applicable to wrist-watches of other designs or other kinds of watches wherein it is necessary to provide the case with one or more 65 appendages.

As shown in Figs. 1 to 7, what corresponds to the watch-case center in usual constructions is made up of two pieces. These are what I here term the watch-case center 1 and 70 the movement-ring. The watch-case center 1, throughout the greater part of its extent, is a narrow flat ring 2, which shape is modified to the extent of having at opposite sides the strap lugs 3, each consisting of the arms 75 4 projecting out from the ring-shaped part 2 and having their outer ends joined by the straight round bar 5. These arms 3 upon the ring-shaped part of the center 1 are spaced such a distance and the bar connecting them 80 is of such length as to admit around the bar 5 between the lugs 3 the strap 6 (shown by dotted lines only in Figs. 1 and 3). Not only do these lugs 3 extend laterally outwardly in their spaced-apart relation, but 85 they curve backwardly so as to throw the bars 5 considerably below the plane of the back of the main ring-shaped part of the watch-case center 1. Midway between the two strap-lugs at the top is the stem-lug or 90 projection for forming the tube that admits the setting and winding mechanism.

The inside of this main ring-shaped part of the center 1 is made truly circular and is internally threaded. The inner part of the 95 construction, which I term the movement-ring 7, is simply a rather broad, thin, circular ring externally threaded to screw into the internal threads of the part 1. It is of such greater width than the part 1 into 100 which it is screwed that it is adapted to project a material distance at the front and rear when it has been screwed into the proper position in the part 1. Interiorly, at the

rear, this ring 7 preferably has the annular boss 8 for suitably supporting the watch-movement in the well-known manner. It will be understood that the movement may be mounted in this ring in any suitable manner, and this detail of watch construction is not a part of the present invention and need not be any more fully shown or described herein.

When this ring 7 is thus screwed into the center 1 so that it projects a suitable distance at front and rear, its projecting threaded edge parts are thus adapted to receive, respectively, the back 9 and the bezel 10 to screw up tightly against the surrounding plane surfaces of the center 1. The bezel 10 is here shown as supporting a crystal 11, which is shown as being mounted in a well-known manner. It will be understood that any suitable crystal may be mounted in the bezel 10 in any suitable manner; or that any other desired front piece may take the place of the bezel 10 and crystal 11, as circumstances may require, in the provision of various kinds of watch cases or movements, or other cases.

In the modification shown in Fig. 8 there is no separate movement ring; the center 1' having the front and rear annular projections 12 and 13, respectively, which are exteriorly threaded to receive the bezel or the like and the back.

As shown in Figs. 9 and 10, the center 1" has the front and rear annular projections 12' and 13' which are not externally threaded but are slightly undercut so that the bezel or the like and the back may be "snapped" on in the well-known manner.

In any of these examples, according to the preferred embodiment of my invention, the center 1, 1' or 1", as the case may be, has the strap-lugs 3, including their arms 4 and bars 5, and the stem-lug 14, all formed integrally of a single piece of metal. This is preferably done by cutting from sheet metal of a suitable gage a blank which is drawn and pressed into shape in such a manner that a minimum of machine or hand work is necessary thereon after this shaping operation.

In the example of Figs. 1 to 7 where this center is to receive the separate ring 7 it is, after being thus shaped with its integral lugs, bored and threaded on its interior, as before described. The movement-ring 7 which has been drawn, pressed or otherwise suitably shaped, and which has been threaded on its exterior, is screwed into the center 1 with its front and rear edges projecting as before described. Then, while it is held in this position, it is fastened in the center 1. As here shown, this is done by means of a pin 15 which is driven into holes bored through one side of the center 1 and

the adjacent side of the ring 7. After the ring 7 has thus been fixed in the center 1, a passage is bored through the stem-lug 14, and the adjacent side of the ring 7 to admit the stem-arbor 16 (Fig. 2). These parts are now ready to receive the watch movement and the back and bezel, as before described.

Before putting the ring 7 into the part 1, it is preferable to grind and lap the front and rear surfaces of the part 1 so that they will be true planes. Then if the bearing surfaces of the back and bezel have been similarly treated, these parts can be brought into very close relation with the center, making a ground joint adapted to exclude virtually all dirt or moisture regardless of the length of time of exposure of the watch. This closeness of fitting of the back and bezel to the center is not due merely to the true-ness of their surfaces, but to the possibility of slight displacement of the ring 7 relatively to the part 1 into which it is screwed. This is due to the inevitable slight play permitted between the two parts thus threaded together. It is thus possible for the back and bezel, which also have the very slight play between their threads and those of the parts 7, to adjust themselves perfectly to the center, even though some of these parts should happen not to be threaded exactly along an axis at right angles to the planes of contact. In fact, it is almost impossible to insure such accuracy of threading; but my improved construction permits of a practically invisible and impenetrable joint, even though such inaccuracies in threading are not to be avoided.

The use of the separate ring 7 has another advantage in that the thread of the annular projections or risers constituted by the edges of this ring are continuous up to the flat faces of the center 1. Thus, full advantage is taken of the height of the projection or riser; whereas, if the thread is chased on an integrally formed riser as shown in Fig. 8, the thread must be discontinued short of the adjacent faces of the center to provide clearance for the threading tool, generally sacrificing from one-fourth to one-fifth of the height of the riser. This is also true if the thread is spun on the integrally formed riser; because a fillet will have to be left at the bottom, and a corresponding chamfer will have to be made on the edge of the back or the bezel to clear this fillet. There is, therefore, a loss of thread whether the thread is chased or spun on the integral riser.

It will be understood, however, that the center with its integrally formed appendages may also have these risers 12 and 13 formed integrally with it, as shown in Fig. 8, should it not be desired to avoid the disadvantages just pointed out; and when the

back and bezel are to "snap" on, this formation of the annular projections or risers 12 and 13' with the center, as shown in Figs. 9 and 10, is not attended with serious disadvantage. It will be seen in such examples as those of Figs. 8, 9 and 10 the entire structure of the watch case, with the exception of its back and bezel or other closures, is made integrally of one piece of metal.

When the watch-case center is thus made, its projections or risers 12 and 13 of Fig. 8, or 12' and 13' of Figs. 9 and 10, are advantageously formed as indicated in Fig. 10. That is, the watch-case center is pressed 15 into shape with its appendages, such as the strap-lug 3 integral therewith, and with extra metal in its interior wall. An annular groove 17 should be formed in this inner wall, thus dividing this extra metal into two parts 18 and 19. Then these parts may 20 be pressed outward in opposite directions by spinning and may thus be made to form the oppositely projecting risers 12' and 13' of Figs. 9 and 10; or, it will be understood 25 that these parts when thus pressed out will be externally threaded to form the projections or risers 12 and 13 of Fig. 8.

It will be seen that whether the annular projections or risers be provided by inserting a separate ring as in Figs. 1 to 7, or whether they be formed integrally with the center as just described, the watch-case center, according to the disclosure herein, may be blanked out of heavy sheet metal with 35 much less waste of material and labor than if the material from which the center is made were thick enough to form these risers *in situ*. It will be seen that the strap-lugs, although ultimately being set back from the 40 watch-case center, are readily formed out of the flat sheet when the piece is blanked; and when they may be curved back during the pressing operation which gives the piece its final form. Likewise, the stem-lug or 45 pendant-tube 14 requires no extra thickness, but is given its round formation, in which it is preferably very slightly thicker than the main part of the center, during the pressing and forming operation. It will 50 be understood that these observations apply, whether the risers are formed of a separate ring or are formed integral with the center, as hereinbefore described.

The important advantage of forming the 55 appendages, such as the strap-lugs and the pendant-tube or stem-lug integral with the center, is the elimination of distortion of the parts such as always occurs where these appendages are made separately and then 60 secured on the center by soldering, welding, brazing or the like. In my improved construction, all of these parts are formed of one piece practically in the same operations, and there is no need of heating the

part at any time. Therefore, the formation 65 of the threads and the truing of the faces of the watch-case center, and other operations requiring great accuracy, are not disturbed as is always the case where the part is heated in soldering, welding or 70 brazing, and is thereby warped and stretched or shrunken out of shape to properly receive the back, bezel or other closure.

In addition to these advantages of having the parts integral, there is also, of course, 75 the saving of highly skilled labor which is required to fasten the separately formed appendages on the watch-case center according to constructions heretofore disclosed.

Moreover, the watch-case center with its 80 appendages integrally formed is a much more substantial and durable article. Where these appendages are made separately and fastened on, they are very seldom securely 85 enough fastened and many of them eventually come loose. If one of the strap-lugs separates from the center, this results in losing the watch; and even if the watch is not lost, it is necessary to practically rebuild 90 and refinish the case in order to replace the lug.

It will be seen, therefore, that by making the watch-case center with all of its appendages integral therewith and preferably so making it that it can be formed from a sheet 95 of metal of about the thickness of its main part between its two opposite flat faces, and depending upon a later operation to supply the lateral annular projections or risers, there is a saving of material and labor and 100 a great increase in the accuracy of fitting of the parts of the case and greatly added strength and durability.

While I have shown and described particularly a wrist-watch, it will be understood that my invention is applicable to 105 other watches, as well as to other cases such as those for compasses and the like. Therefore, while certain constructional details are deemed preferable in connection 110 with my invention, and I have shown and described these rather specifically in elucidating the construction and use of my invention, as is required, I do not wish to be understood as being limited to such precise showing and description, but having 115 thus fully described my invention, what I claim as new and desire to secure by Letters Patent is:

1. As a new and improved article of 120 manufacture, a case center having an appendage integral with its peripheral wall, and having substantially plane opposite faces, said center and said peripheral projections being blanked from a sheet of metal 125 of substantially the thickness of said center between said faces, and projections or risers around adjacent to the inner wall

of said center to hold closures on said center against said faces, said projections or risers being brought into place by an additional operation after said center has been blanked from said sheet.

5 2. The method of making a case center having an appendage integral with its peripheral wall and having substantially plane opposite faces, and having projections or 10 risers around adjacent to the inner wall of said center to hold closures on said center

against said faces, which comprises blanking said center from a sheet of metal of substantially the thickness of said center between said faces, and bringing said projections or risers into place by an additional operation after said center has been blanked from said sheet. 15

ARTHUR W. WADSWORTH.
